US00D821755S

(12) **United States Design Patent** (10) **Patent No.:** **US D821,755 S**
(45) **Date of Patent:** **** Jul. 3, 2018**

(54) **TOOTHBRUSH**

(71) Applicant: **Colgate-Palmolive Company**, New York, NY (US)

(72) Inventors: **Eduardo Jimenez**, Manalapan, NJ (US); **Robert Moskovich**, Manakin-Sabot, VA (US); **Michael Rooney**, Millburn, NJ (US); **Joachim Storz**, Zell am See (AT); **Raimund Klausegger**, Vienna (AT); **Andreas Wechsler**, Zell am See (AT)

(73) Assignee: **Colgate-Palmolive Company**, New York, NY (US)

(**) Term: **15 Years**

(21) Appl. No.: **29/639,839**

(22) Filed: **Mar. 9, 2018**

Related U.S. Application Data

(60) Continuation of application No. 29/443,323, filed on Jan. 16, 2013, which is a division of application No. (Continued)

(57) **CLAIM**

The ornamental design for a toothbrush, as shown and described.

DESCRIPTION

FIG. 1 is a right front perspective view of a toothbrush according to a first embodiment of the new design; FIG. 2 is a left front perspective view thereof; FIG. 3 is a right rear perspective view thereof; FIG. 4 is a left rear perspective view thereof; FIG. 5 is a front elevation view thereof; FIG. 6 is a rear elevation view thereof; FIG. 7 is a right-side elevation view thereof; FIG. 8 is a left-side elevation view thereof; FIG. 9 is a top plan view thereof; and, FIG. 10 is a bottom plan view thereof.

The broken lines in the drawings illustrate portions of the article that form no part of the claimed design.

1 Claim, 5 Drawing Sheets

Related U.S. Application Data

29/352,273, filed on Dec. 18, 2009, now Pat. No. Des. 675,830.
